METHOD OF MANUFACTURING HOSIERY

Robert E. Claussner, Paducah, Ky., assignor to
 Union Special Machine Company, Chicago, Ill.,
 a corporation of Illinois

Application July 23, 1949, Serial No. 106,401

13 Claims. (Cl. 112—262)

1

This invention pertains to the art of manufacturing stitched articles, and more particularly to the manufacture of hosiery from hosiery blanks by an improved method of and sewing unit for facilitating the handling of such blanks in the course of carrying out successive operations with respect thereto.

It is believed that the nature of the present invention will be better understood by first outlining the method employed in many mills today in the manufacture of hosiery. Accordingly, a brief discussion of the most common present-day method of manufacture follows.

It has heretofore been the practice in modern hosiery mills for the knitting machine operator to pick up hosiery blanks produced by a knitting machine and tie them in bundles of one dozen pairs and deposit the bundles, usually three in number, in nylon mesh bags. The bags containing the blanks are trucked to a stockroom where the stockroom girl transfers them to stock bins. At this time the stockroom girl checks the number of bundles in each bag and the contents of occasional bags selected at random, counting the number of stockings in each bundle of such bags for the purpose of checking the accuracy of the knitter who tied the bundles.

As work is required in the looper department, a supply of bundles of blanks is transported from the stockroom to looper machines and deposited there in hampers from which they are withdrawn by looper machine operators (hereinafter referred to as "loopers"), as required. A looper unties a bag, removes a bundle of blanks, performs customary looper operations in the foot portion of each blank, folds the looped blanks, and returns them to the bag which is eventually retied. The bags are then returned to the stockroom and stored there in bins until they are needed for the seaming operation. Recounting of the blanks usually takes place at this time.

The bag and contents are next taken to seaming machine operators (hereinafter referred to as "seamers") who provide the long seam in the foot and leg portions and then return the partially completed stockings in the bags to the stockroom girl.

Following seaming, the bundles of hosiery are ready for Greige inspection. The bags of seamed bundles of hosiery are conveyed to the Greige inspection department and there deposited in bins. The Greige inspector (hereinafter referred to as "inspector") unties a bag and removes one bundle of hosiery at a time, and inspects the seamed hose in the usual manner, segregating

2

all first quality products from defective products, after which they are again placed in bags and retied. Defective hosiery is accumulated and taken to the seamers for reworking, after which they are returned, re-sorted and reexamined by the inspector. These hose are next reclassified as to quality. Bags of finally inspected work are then gathered, and first quality products are segregated from "irregulars," "seconds," etc. The hose are then conveyed to the dye house stockroom where they are stored until they are needed for the next operation, which is known as the "Dunn" or preshrinking operation.

It is evident from the foregoing that present-day practice requires repeated placing and removing of bundles of partly completed hosiery into and from the nylon mesh bags, tying and untying the bags, checking and rechecking hosiery in individual bundles, and moving the bags and their contents to and from stockrooms, the looper machine department, the seaming machine department, and the Greige inspection department, which generally occupy separate and distinct areas in a mill. This necessitates considerable handling which has long been recognized as constituting an important cost factor.

Further, the hosiery blanks are generally subjected to undesirable twisting, wrinkling or crushing due to their being placed and transported in the mesh bags, thereby making it more difficult for loopers and seamers to handle them. The same is true where boxes are employed to transport bundles of hose from one department to another. The use of such boxes is additionally objectionable in that it may result in snagging of hosiery.

Another objection to conventional methods is that a seaming machine may be out of adjustment for several days before hose having faulty seams resulting therefrom are discovered upon examination by the inspector. This may be very costly as many dozens of hose will have been improperly seamed before inspection indicates that a particular seaming machine is out of adjustment and necessary steps are taken to readjust the machine.

The method and apparatus of this invention overcome the objections outlined above and facilitate the manufacture of hosiery on a mass production basis at a substantial reduction in costs. It has been ascertained that by grouping certain apparatus in operating units, each unit comprising a looper machine, a plurality of seaming machines and a Greige inspection table, arranged in predetermined relation, and by han-

dling the hosiery blanks in a manner to be described in detail hereinafter, hosiery blanks may be converted into looped and seamed hose with greater efficiency, and with corresponding reduction in cost, than has been heretofore possible.

In carrying out the method of this invention, the hosiery blanks turned out by a knitting machine are gathered and tied together at their upper ends in bundles of one dozen pairs per bundle. The bundles are suspended on portable C-frames, preferably eight bundles to the C-frame, which allows the blanks to hang full-length, thereby eliminating objectionable twisting, wrinkling or crushing. This permits the stockroom girl to readily check the number of bundles supported by each C-frame and the number of blanks in any bundle without the necessity of handling the individual blanks.

A plurality of C-frames carrying bundles of hosiery blanks is supported on a truck which is rolled to an operating unit where the C-frames, and bundles suspended therefrom, are transferred as required to a supporting rack at the looper machine. The looper removes one bundle of blanks at a time from a C-frame, performs the customary looping operation on the toe and/or heel portion of each blank in the bundle and replaces the bundle on an empty C-frame. It is not necessary for the looper to untie the bundle in carrying out the looping operations.

The looping machine is positioned substantially equi-distantly from a plurality of seaming machines, preferably three. The operators of two of these machines may face in the same direction as the looper while the operator of the third seaming machine may be located rearwardly and to one side of the looping machine and so positioned that the operator thereof normally faces in a direction opposite to that of the looper and the first mentioned pair of seamers. Substantially directly behind the looping machine is a Greige examining table so arranged that the inspector normally faces a direction opposite to that of the looper.

As work is required by individual seamers, the looper passes C-frames containing bundles of looped work directly to a particular seamer without either operator leaving her seat. The seamer removes a bundle of work received from the looper, unties the bundle, seams each blank in the bundle, then reties the hose in a bundle, and places the bundle on another C-frame. The C-frames containing seamed hose are passed by individual seamers to the inspector, as called for. The inspector removes the bundle of seamed hose and inspects the pieces of work in the usual manner. Inasmuch as the seamer passes her work directly to the inspector, and since the inspector keeps pace with the seamers in her unit, it is apparent that the inspector is able to promptly detect faulty seams resulting from a particular seaming machine in the unit being out of adjustment. This permits necessary steps to be taken to adjust the machine and, as a consequence, the number of defective hose is thus maintained at a minimum. Preferably each C-frame carries an identifying tag to indicate which of the three seaming machines of the unit performed the seaming operation on the blanks carried by the frame.

It is a principal object of the invention to effect substantial reductions in the handling of hosiery blanks in the course of converting the same into seamed hose.

Another object of the invention is to correlate,

facilitate and expedite looping, seaming, and Greige inspection operations in the manufacture of hosiery on a mass production basis.

Another object of the invention is to permit of prompt inspection of seamed hose, whereby the number of defectively seamed hose may be minimized. This also constitutes a distinct advantage because, by arranging for prompt inspection of the output of each seaming machine and identification of each stocking with a particular seaming machine, faulty seams due to misadjustment of a seaming machine are quickly detected. Necessary steps to adjust the machine may then be taken without delay and the number of defective hose is kept at a minimum.

Another object of the invention is to eliminate the possibility of hosiery blanks becoming twisted, wrinkled, crushed and/or snagged in the course of conversion into seamed hose.

A further object of the invention is to effect savings in labor costs, permit of efficient use of equipment and materials, and utilize working space to greater advantage than has been heretofore possible in the manufacture of hosiery.

The method of this invention eliminates the need for the nylon mesh bags in the handling of hosiery blanks from the time they leave the knitting machines. Such bags are relatively expensive in initial and upkeep costs and their elimination results in material economies.

The foregoing objects, together with additional objects, as well as the advantages attainable by the practice of this invention, will be readily understood by persons versed in the art upon reference to the following detailed description, taken in conjunction with the accompanying drawings.

In the drawings:

Figure 1 is a plan of a layout illustrating a recommended arrangement of apparatus embodying a plurality of operating units that may be advantageously employed in the practice of this invention.

Figure 2 is an enlarged plan view of one of the operating units shown in Figure 1 and illustrates some of the details of construction of individual pieces of apparatus.

Figure 3 is a plan view of a truck for transporting bundles of hosiery blanks from the knitting department to the looper-seamer department in a hosiery mill employing the invention.

Figure 4 is a view in side elevation of the truck shown in Figure 3.

Figure 5 is a view in end elevation of the truck depicted in Figures 3 and 4. Mounted on the truck is a C-frame from which is suspended a plurality of bundles of freely hanging hosiery blanks. It will be understood that a large number of such frames may be carried by the truck.

Figure 6 is an enlarged view of a rack adapted to be supported by a looper machine of the unit.

Figure 7 is an enlarged top plan view of one of the seaming machines shown in Figure 2, certain parts being omitted for better illustration.

Figure 8 is an elevational view of the seaming machine shown in Figure 7.

Figure 9 is an enlarged view, partly in vertical central cross section and partly in elevation, of a stocking-suspending device employed in connection with the invention, the parts being shown in one relative position.

Referring now to the drawings wherein like reference characters denote corresponding parts

throughout the several views, a truck generally indicated by numeral 10 is adapted to transport bundles of hosiery blanks from a knitting room in a mill directly to a looper-seamer department of the type indicated in the layout of Figure 1. The truck comprises a skeleton base 11 including a stretcher 12 of angle iron construction and mounted on swivel casters 13. Extending upwardly from base 11 are four inclined tubular supports 14 that are connected at their upper ends to a channel cross bar 15. Projecting laterally from each side of cross bar 15 is a series of spaced rods 16 which are parallel to the plane of base 11. The free end of each rod 16 is upturned, as indicated at 17 in Figure 5. A C-frame 20 having a pair of hooks 21 is adapted to be readily mounted on and subsequently removed from each rod 16. Hosiery blanks 22 are rolled and tied together at their upper or welt ends by soft cords or fabric strips 23 to obtain bundles of blanks 24. Each bundle preferably contains two dozen blanks. Eight bundles of blanks are adapted to be suspended on each C-frame, as shown in Figure 5, with the individual blanks in each bundle hanging freely.

Figure 1 discloses diagrammatically a layout of a section of a combined looper-seamer-inspection department in a mill and illustrates a plurality of operating units, namely, five, a typical operating unit layout being shown in greater detail in Figure 2. Each operating unit comprises a looper machine L, preferably three seaming machines S, and a Greige inspection table I. Each looper in the section is provided with a chair LC, each seaming machine with a chair SC, and each inspection table with a chair IC.

Looper machine L, seaming machines S, and inspection table I are grouped to obtain the arrangement shown in Figure 2. This grouping constitutes one of the features of the invention and contributes materially to the attainment of the objects of the invention. As will be observed from an examination of Figure 2, the looper machine is positioned substantially midway between a pair of the seaming machines, and the operators of these machines, when seated, normally face in the same direction. The third seaming machine is located rearwardly and to one side of the looper's chair LC. The machines and corresponding chairs are so positioned with respect to each other that the looper may pass bundles of hosiery blanks directly to any of the seamers, as indicated by arrows A, while these operators remain seated at their respective machines. Inspection table I is located adjacent the third seaming machine and the inspector's chair IC is directly rearward of the position normally occupied by the looper. This permits ready passing of bundles of looped and seamed hosiery blanks by any of the seamers directly to the inspector, as indicated by arrows B.

Looper machines L may be of any desired known construction adapted to loop the toe and/or heel portion of hosiery blanks and may be the same as or similar to the machine disclosed in De Spain Patent 2,050,563, dated August 11, 1936, and entitled "Looper." Secured to and projecting laterally of one side of each looper machine is a bar 25 that carries an upstanding tubular post 26 provided with a tubular horizontal arm 27 at its upper end (Figure 6). Tubular arm 27 supports parallel horizontal rods 28, two such rods projecting from one side of the arm and a third rod projecting from

the other side of the arm. Each rod 28 is upturned at its free end 29 and is adapted to be engaged by hooks 21 of a corresponding C-frame 20 previously loaded with one or more bundles of freely hanging hosiery blanks.

Reference is next had to Figure 2, 7 and 8 for an understanding of the construction of seaming machines S which are preferably identical. Each seaming machine comprises a base 30 that supports a tubular pedestal 31 on which is mounted a vertically adjustable table 32. Positioned on the table and overhanging the forward edge thereof is a cup feed seaming machine 33 that includes feed cups 34 which are rotatable about spaced-apart parallel vertical axes. Machine 33 may be the same as or similar to the sewing machine disclosed in Rubel Patent 2,133,229, dated October 11, 1938, entitled "Sewing Machine," to which reference may be had for further details of construction.

An electric transmitter 35, preferably of the type illustrated and described in Le Vesconte et al. Patent 2,390,220, dated December 4, 1945, and entitled "Sewing Machine Drive," is mounted beneath the rearward portion of table 32. Machine 33 is driven by electric transmitter 35 through the intermediary of a V-belt 36 that is partially encased in a belt guard 37.

A pair of foot treads 39 and 40 is pivotally mounted in base 30. An adjustable rod means 41 for controlling the operation of electric transmitter 35 is connected at its lower end to foot treadle 40 and at its upper end to the clutch operating arm of the transmitter. A flexible cable 42, coated with a suitable plastic material, is connected at its lower end to treadle 40 and at its upper end to a lever 43 which cooperates with devices (not shown) upon actuation of treadle 40 to effect separation of feed cups 34 in the manner disclosed in Hacklander Patent 2,043,749, dated June 9, 1936, and entitled "Feeding Mechanism for Sewing Machines." A knee press pad 44 depends from a bracket 45 that is attached to pedestal 31 and is coupled to a chain connector 46 which, upon actuation of the knee pad, coacts with other devices (not shown) to raise an uncurler (not shown) which is preferably of a type adapted to compensate for heavier reinforced portions of hosiery blanks, such as that disclosed in Kucera Patent 2,292,762, dated August 11, 1942, and entitled "Overedge Sewing Machine." Table 32 is provided with a pair of integral upwardly projecting bosses 47 and 48. A post 49, which extends through and beyond boss 47 and the table, is vertically adjustable as allowed by a set screw 50. Mounted on the upper end of post 49 is a conventional thread stand 51 (Figure 2) which carries a plurality of cones of thread 52.

Referring next to Figures 7 and 8, a rack 55 is provided which comprises a straight lower tubular support 56 and an L-shaped intermediate tubular support 57. Tubular supports 56 and 57 are adjustably secured to post 49 by screws 58 and 59, respectively. Rack 55 also includes an upstanding tubular post 60 which carries a horizontally arranged tubular arm 61 at its upper end. Secured to and projecting laterally from tubular arm 61 is a plurality of parallel horizontal rods 62, each of which is upturned at its free end 63. As is shown in Figure 7, a pair of rods 62 projects from one side of arm 61, while a third rod projects from the other side of the arm. Each rod 62 is adapted to receive and support a C-frame 20 by means of the hooks 21 carried by the latter.

A trough 65, generally semi-circular in transverse cross section, is supported in a position intermediate feed cups 34 and the lap of the seamer, when seated at her machine S, by devices that will now be described. For this purpose, there is provided a pair of bent rods 66 and 67 that are attached, by welding or the like, to the end portions of the rear lip of the trough. The trough and its rods are preferably coated with a suitable plastic material to prevent snagging of looped blanks in the course of seaming the same. Rod 66 is attached to a T-connector 68 by a screw 69, and the T-connector is, in turn, fastened to post 69 by a screw 70 (Figure 8). Rod 67 is in like manner attached to a T-connector 71 by a screw (not shown). T-connector 71 is secured to a post 72 by a screw 73. Post 72 is, in turn, held adjustably in the boss 48 by a set screw 74. This arrangement permits of ready vertical and horizontal adjustment of trough 65 with respect to machine 33.

An inclined tray 75 is attached to rod 66 by a bracket 76. As is best shown in Figure 7, the tray is conveniently located to one side of feed cups 34 so that the seamer may drape seamed hosiery blanks thereon. The tray is also preferably coated with a suitable plastic material to minimize the possibility of snagging hosiery blanks.

The Greige inspection table I may be of any known construction and includes a hosiery form 77 (Figure 2) which is disposed between the front edge of the table and the inspector's chair, and is pivoted at 78 to an arm 79. The form and its support may be of any of the well-known constructions.

A rack 80, similar in a number of respects to the rack shown in Figure 6 and including horizontal rods 81, is secured to one corner of the inspection table. Each rod 81 is adapted to receive a C-frame 20 or a plurality of stocking-suspending devices 82, which are best shown in Figure 9. Each device 82 includes a spindle 83 having a hook 84 at its upper end, a slotted tube 85 concentric with the spindle, and a spring 86. The spindle carries a ring 87 that is provided with a series of needless 88, a stripping plate 89, and a needle-protecting shroud 90 that is slideable along tube 85. Each stocking-suspending device may be the same as or similar to the device disclosed in Dunn et al. Patent 2,340,520, dated February 1, 1944.

In the practice of this invention, hosiery blanks produced by a knitting machine are picked up at the knitting machine by the knitter and rolled at their upper or welt ends in bundles, preferably one dozen pairs of blanks to a bundle, each bundle is tied at its upper end by a strip of fabric 23, and suspended on a C-frame 20 by passing the loop of the cord or strip over the lower free arm of the frame. Each illustrated C-frame accommodates eight bundles of blanks. Loaded C-frames are placed on rods 16 of truck 10 so that the individual blanks in each bundle hang freely, thereby eliminating the possibility of their becoming crushed, twisted or wrinkled. A checker may easily and quickly count the number of bundles on a particular loaded C-frame and the number of blanks in each bundle without untying the bundles.

After the truck is loaded with from 208 to 416 dozen pairs of blanks, it is rolled from the knitting department into the looper-seamer department, a section of which is shown in Figure 1. There, two loaded C-frames are suspended from a pair

of rods 28 adjacent looper machine L. An empty C-frame is mounted on the remaining rod 28. The looper removes a bundle of blanks from a C-frame and loops the toe and/or heel portion of each blank in the bundle with the aid of looper machine L. The bundle remains tied during this procedure. Upon completion of the looping of all blanks in a bundle, the looper suspends the bundle of looped blanks on the empty C-frame 10 with the blanks hanging freely. The looper repeats this procedure for each bundle of blanks until eight bundles of looped blanks are placed on the previously empty C-frame.

As work is required by individual seamers, the 15 looper hands a C-frame loaded with bundles of looped blanks to a seamer who places the frame on a rod 62 of rack 55. The seamer removes a bundle of blanks from rack 55, unties fabric strip 23, and deposits the blanks along trough 65. 20 She then takes one blank at a time and places seaming machine 33 in service, whereupon the blank is passed therethrough and seamed, from the tip of the toe to the top of the welt, along the bottom of the foot and up the back of the 25 leg portion, in the conventional manner. Each looped and seamed blank is then draped over tray 75 adjacent the seaming machine 33. When all blanks in a bundle have been seamed, the seamer collects them from tray 75 and reties them into 30 a bundle at their upper ends by means of the strip of fabric. Bundles of looped and seamed hosiery are placed on another C-frame mounted on rack 55, and after that C-frame is filled, it is transferred to inspection table I where it is suspended on a rod 81 of rack 80 so that the individual blanks hang freely.

The inspector then unties a bundle of looped and seamed hosiery and inspects each piece of work on form 77. The inspector classifies 40 inspected products, segregating the products into first quality merchandise, "seconds," etc. First quality products are mounted on one of the suspending devices 82 which is supported on the arm 81 of rack 80. Devices 82, when loaded, are transferred to a rack R (Figure 1) adjacent inspection table I. A number of the devices may, if desired, be temporarily suspended from the arm 81 of rack 80. Rack R may be of any suitable construction, preferably having arms with recesses or depressions adapted to receive and retain the hooks 84 of devices 82. When the rack becomes loaded, it is transferred to a cabinet where the hosiery is preset. This cabinet may 50 suitably be of the type known as the "Dunn" 55 cabinet, disclosed in the patent to Dunn 2,350,021, granted May 30, 1944.

Inasmuch as an inspector handles work produced by the looping and seaming machines in her operating unit, and since the inspector is 60 normally able to keep pace with merchandise produced by these machines, she can readily and quickly detect products that are defective due to faulty looping or seaming. The inspector may bring these to the attention of the operator of the machine where the fault occurred, and if that machine is out of adjustment, necessary steps may be taken promptly to rectify the condition. This greatly minimizes the number of defective hose produced in the mill. Since each 65 inspector is responsible for the output of only a single looper, the source of looper defects is immediately identified. The inspector also will know from which seamer each C-frame is received and thus identify the source of defective 70 seams. If desired, however, each C-frame may

be provided with a tag identifying it with a particular seaming machine and also a particular knitting machine to facilitate determination of the source of the trouble.

Pieces of work that may be defective in minor respects are transferred to the mending table M (Figure 1) where a mender makes the necessary repairs. Such merchandise is then returned to the inspection table where it is re-examined and reclassified. It has been found that one mender is capable of repairing the defective goods produced by five of the looping and seaming units so that, as shown in Figure 1, only one mender is provided for five such units.

From the foregoing, it is believed that the many advantages obtainable by the practice of the present invention will be readily apparent to persons skilled in the art. However, since certain changes may be made in carrying out the above method without departing from the scope of the invention as defined by the appended claims, it is intended that all matter contained herein shall be interpreted as illustrative and explanatory, rather than in a limiting sense.

I claim:

1. In a method of manufacturing hosiery the steps comprising transporting a predetermined number of hosiery blanks tied together at their upper ends to obtain a bundle of freely hanging blanks to a looper machine of an operating unit that comprises said looper machine and a plurality of seaming machines so arranged with respect to the looper machine that the looper machine operator may pass quantities of hosiery blanks to each seaming machine operator while said operators are positioned at their respective machines, looping at least the toe portion of each blank in the bundle, said blanks remaining tied together during such looping, passing a bundle of looped blanks directly to any selected one of the seaming machine operators, untying the bundle and seaming the blanks at the selected seaming machine, retying looped and seamed blanks into a bundle at the seaming machine and suspending the bundle adjacent the seaming machine so that the individual looped and seamed blanks hang freely.

2. In a method of manufacturing hosiery the steps comprising tying predetermined numbers of hosiery blanks, produced by a knitting machine, at their upper ends to obtain bundles of freely hanging blanks, transporting said bundles directly to a looper machine of an operating unit that comprises said looper machine and a plurality of seaming machines so arranged with respect to the looper machine that the looper machine operator may pass quantities of hosiery blanks to each seaming machine operator while said operators are positioned at their respective machines, looping at least the toe portion of each blank in the bundle, said blanks remaining tied together during such looping, passing a bundle of freely hanging looped blanks directly to any selected one of the seaming machine operators, untying the bundle and seaming the blanks at the selected seaming machine, retying looped and seamed blanks into a bundle at the seaming machine and suspending the bundle adjacent the seaming machine so that the individual looped and seamed blanks hang freely.

3. In a method of manufacturing hosiery the steps comprising transporting a predetermined number of hosiery blanks tied together at their upper ends to obtain a bundle of such blanks to a looper machine of an operating unit that com-

prises said looper machine, a plurality of seaming machines so arranged with respect to the looper machine that the looper machine operator may pass quantities of hosiery blanks to each seaming machine operator while said operators are positioned at their respective machines, and an inspection table, looping the toe portion of each blank in the bundle, said blanks remaining tied together during the looping thereof, passing the bundle of looped blanks directly to any selected one of the seaming machine operators, untying the bundle and seaming the blanks at the selected seaming machine, retying looped and seamed blanks into a bundle at the seaming machine, and transferring the bundle of looped and seamed blanks to the inspection table.

4. In a method of manufacturing hosiery the steps comprising transporting bundles of freely hanging hosiery blanks tied at their upper ends to a looper machine of an operating unit that comprises said looper machine, a plurality of seaming machines so arranged with respect to the looping machine that the looping machine operator may pass bundles of hosiery blanks to the operator of any seaming machine, as required, while said operators are stationed at their respective machines, and an inspection table, looping each blank in each bundle, said bundles remaining intact during such looping, passing bundles of looped blanks from the looper machine operator directly to operators of the seaming machines, as required, untying each bundle of looped blanks at a corresponding seaming machine, seaming each looped blank in the untied bundle, retying the looped and seamed blanks into a bundle at the seaming machine, and transferring the bundle of looped and seamed blanks directly from the seaming machine to the inspection table.

5. In a method of manufacturing hosiery the steps comprising tying predetermined numbers of hosiery blanks produced by a knitting machine at their upper ends to obtain bundles of such blanks, transporting said bundles directly to a looper machine of an operating unit that comprises said looper machine, a plurality of seaming machines so arranged with respect to the looper machine that the looper machine operator may pass bundles of hosiery blanks to any seaming machine operator while said operators are stationed at their machines, and an inspection table, looping the foot portion of each blank in said bundles, the bundles remaining tied during said looping, passing bundles of looped blanks from the looper machine operator to seaming machine operators, as required, untying bundles of looped blanks at the seaming machines, retying the looped and seamed blanks into bundles at the seaming machines, and transferring bundles of looped and seamed blanks directly to the inspection table.

6. In a method of manufacturing hosiery the steps comprising tying predetermined numbers of hosiery blanks at their upper ends to obtain bundles of such blanks, suspending the bundles on a support frame so that the blanks in each bundle hang freely, transporting the suspended bundles to a looper machine of an operating unit that comprises said looper machine and a plurality of seaming machines so arranged with respect to the looper machine that the looper machine operator may pass bundles of blanks to each seaming machine operator while said operators are positioned at their respective machines, looping at least the toe portion of each blank in each bundle at the looper machine, said blanks re-

maining tied together during such looping, suspending bundles of looped blanks on a support frame positioned adjacent the looper machine so that the individual looped blanks hang freely, passing bundles of suspended looped blanks from the looper machine operator directly to any selected one of the seaming machine operators, untying bundles of looped blanks and seaming the same at the selected seaming machine, retying looped and seamed blanks into bundles at the seaming machine and suspending such bundles on a support frame adjacent the seaming machine so that the looped and seamed blanks hang freely.

7. In a method of manufacturing hosiery the steps comprising tying predetermined numbers of hosiery blanks at their upper ends to obtain bundles of such blanks, suspending the bundles on a support frame so that the blanks in each bundle hang freely, transporting the suspended bundles to a looper machine of an operating unit that comprises said looper machine and a plurality of seaming machines so arranged with respect to the looper machine that the looper machine operator may pass bundles of blanks to each seaming machine operator while said operators are positioned at their respective machines, looping at least the toe portion of each blank in each bundle at the looper machine, said blanks remaining tied together during such looping, suspending bundles of looped blanks on a support frame positioned adjacent the looper machine so that the individual looped blanks hang freely, passing bundles of suspended looped blanks from the looper machine operator directly to any selected one of the seaming machine operators, untying a bundle of looped blanks at the selected seaming machine and placing the blanks in a trough positioned intermediate the seam-forming elements of the seaming machine and the lap of the operator when seated at that machine, seaming each looped blank, retying looped and seamed blanks into a bundle at the seaming machine and suspending the same on a support frame adjacent the seaming machine so that the looped and seamed blanks hang freely.

8. In a method of manufacturing hosiery the steps comprising tying predetermined numbers of hosiery blanks at their upper ends to obtain bundles of such blanks, suspending the bundles on a support frame so that the blanks in each bundle hang freely, transporting the suspended bundles to a looper machine of an operating unit that comprises said looper machine and a plurality of seaming machines so arranged with respect to the looper machine that the looper machine operator may pass bundles of blanks to each seaming machine operator while said operators are positioned at their respective machines, looping at least the toe portion of each blank in each bundle at the looper machine, said blanks remaining tied together during such looping, suspending bundles of looped blanks on a support frame positioned adjacent the looper machine so that the individual looped blanks hang freely, passing bundles of suspended looped blanks from the looper machine operator directly to any selected one of the seaming machine operators, untying a bundle of looped blanks at the selected seaming machine and placing the blanks in a trough positioned intermediate the seam-forming elements of the seaming machine and the lap of the operator when seated at that machine, seaming each blank, placing looped and seamed blanks on a tray that is positioned to one side of

the seaming machine, retying looped and seamed blanks into a bundle at the seaming machine and suspending the same on a support frame adjacent the seaming machine so that the looped and seamed blanks hang freely.

9. In a method of manufacturing hosiery the steps comprising tying predetermined numbers of hosiery blanks, produced by a knitting machine, at their upper ends to obtain bundles of such blanks, suspending the bundles on a support frame at the knitting machine so that the blanks in each bundle hang freely, transporting the suspended bundles directly to a looper machine of an operating unit that comprises said looper machine and a plurality of seaming machines so arranged with respect to the looper machine that the looper machine operator may pass bundles of blanks to each seaming machine operator while said operators are positioned at their respective machines, looping at least the toe portion of each blank in each bundle at the looper machine, said blanks remaining tied together during such looping, suspending bundles of looped blanks on a support frame positioned adjacent the looper machine so that the individual looped blanks hang freely, passing bundles of suspended looped blanks from the looper machine operator directly to any selected one of the seaming machine operators, untying a bundle of looped blanks at the selected seaming machine and placing the blanks in a trough positioned intermediate the seam-forming elements of the seaming machine and the lap of the operator when seated at that machine, seaming each blank, placing looped and seamed blanks on a tray that is positioned to one side of the seaming machine, retying looped and seamed blanks into a bundle at the seaming machine and suspending the same on a support frame adjacent the seaming machine so that the looped and seamed blanks hang freely.

10. In a method of manufacturing hosiery the steps comprising tying predetermined numbers of hosiery blanks at their upper ends to obtain bundles of such blanks, suspending the bundles on a support frame so that the blanks in each bundle hang freely, transporting the suspended bundles to a looper machine of an operating unit that comprises said looper machine, a plurality of seaming machines so arranged with respect to the looper machine that the looper machine operator may pass bundles of blanks to each seaming machine operator while said operators are positioned at their respective machines, and an inspection table, looping at least the toe portion of each blank in each bundle at the looper machine, said blanks remaining tied together during such looping, suspending bundles of looped blanks on a support frame positioned adjacent the looper machine so that the individual looped blanks hang freely, passing bundles of suspended looped blanks from the looper machine operator directly to any selected one of the seaming machine operators, untying bundles of looped blanks and seaming the same at the selected seaming machine, retying looped and seamed blanks into bundles at the seaming machine, suspending such bundles on a support frame adjacent the seaming machine so that the looped and seamed blanks hang freely, transferring bundles of suspended looped and seamed blanks directly to the inspection table, and suspending such bundles adjacent the inspection table so that the blanks in each bundle hang freely.

11. In a method of manufacturing hosiery the steps comprising tying predetermined numbers

of hosiery blanks at their upper ends to obtain bundles of such blanks, suspending the bundles on a support frame so that the blanks in each bundle hang freely, transporting the suspended bundles to a looper machine of an operating unit that comprises said looper machine, a plurality of seaming machines so arranged with respect to the looper machine that the looper machine operator may pass bundles of blanks to each seaming machine operator while said operators are positioned at their respective machines, and an inspection table, looping at least the toe portion of each blank in each bundle at the looper machine, said blanks remaining tied together during such looping, suspending bundles of looped blanks on a support frame positioned adjacent the looper machine so that the individual looped blanks hang freely, passing bundles of suspended looped blanks from the looper machine operator directly to any selected one of the seaming machine operators, untying bundles of looped blanks at the selected seaming machine and placing the blanks in a trough positioned intermediate the seam-forming elements of the seaming machine and the lap of the operator when seated at that machine, seaming each blank, retying looped and seamed blanks into bundles at the seaming machine, suspending the same on a support frame adjacent the seaming machine so that the looped and seamed blanks hang freely, transferring bundles of suspended looped and seamed blanks directly to the inspection table, and suspending such bundles adjacent the inspection table so that the blanks in each bundle hang freely.

12. In a method of manufacturing hosiery the steps comprising tying predetermined numbers of hosiery blanks at their upper ends to obtain bundles of such blanks, suspending the bundles on a support frame so that the blanks in each bundle hang freely, transporting the suspended bundles to a looper machine of an operating unit that comprises said looper machine, a plurality of seaming machines so arranged with respect to the looper machine that the looper machine operator may pass bundles of blanks to each seaming machine operator while said operators are positioned at their respective machines, and an inspection table, looping at least the toe portion of each blank in each bundle at the looper machine, said blanks remaining tied together during such looping, suspending bundles of looped blanks on a support frame positioned adjacent the looper machine so that the individual looped blanks hang freely, passing bundles of suspended looped blanks from the looper machine operator directly to any selected one of the seaming machine operators, untying a bundle of looped blanks at the selected seaming machine and placing the blanks in a

in a trough positioned intermediate the seam-forming elements of the seaming machine and the lap of the operator when seated at that machine, seaming each blank, placing looped and seamed blanks on a tray that is positioned to one side of the seaming machine, retying looped and seamed blanks into a bundle at the seaming machine, suspending the same on a support frame adjacent the seaming machine so that the looped and seamed blanks hang freely, transferring bundles of suspended looped and seamed blanks directly to the inspection table, and suspending such bundles adjacent the inspection table so that the blanks in each bundle hang freely.

13. In a method of manufacturing hosiery the steps comprising tying predetermined numbers of hosiery blanks, produced by a knitting machine, at their upper ends to obtain bundles of such blanks, suspending the bundles on a support frame at the knitting machine so that the blanks in each bundle hang freely, transporting the suspended bundles directly to a looper machine of an operating unit that comprises said looper machine, a plurality of seaming machines so arranged with respect to the looper machine that the looper machine operator may pass quantities of hosiery blanks to each seaming machine operator while said operators are positioned at their respective machines, and an inspection table, looping at least the toe portion of each blank in each bundle, at the looper machine, said blanks remaining tied together during such looping, suspending bundles of looped blanks on a support frame positioned adjacent the looper machine so that the individual looped blanks hang freely, passing bundles of suspended looped blanks from the looper machine operator directly to any selected one of the seaming machine operators, untying a bundle of looped blanks at the selected seaming machine and placing the blanks in a trough positioned intermediate the seam-forming elements of the seaming machine and the lap of the operator when seated at that machine, seaming each blank, placing looped and seamed blanks on a tray that is positioned to one side of the seaming machine, retying looped and seamed blanks into a bundle at the seaming machine, suspending the same on a support frame adjacent the seaming machine so that the looped and seamed blanks hang freely, transferring bundles of suspended looped and seamed blanks directly to the inspection table, and suspending such bundles adjacent the inspection table so that the blanks in each bundle hang freely.
